CLAIM

I claim the ornamental design for a hanger, as shown and as described.

DESCRIPTION

FIG. 1 is a perspective view of a hanger.

FIG. 2 is the front view of the hanger.

FIG. 3 is a back view of the hanger.

FIG. 4 is a side view of the hanger.

FIG. 5 is a second side view of the hanger.

FIG. 6 is a top view of the hanger.

FIG. 7 is bottom view of the hanger; and,

FIG. 8 is a perspective view of the hanger shown in environmental use.

The broken lines shown represent unclaimed subject matter and form no part of the claimed design.
